CLAIM

We claim a new ornamental design for a charm, as shown and described.

DESCRIPTION

FIG. 1 is a perspective view of a charm according to a second preferred embodiment of our new design;

FIG. 2 is a front elevational view of the charm of FIG. 1;

FIG. 3 is a rear elevational view of the charm of FIG. 1;

FIG. 4 is a left side elevational view of the charm of FIG. 1;

FIG. 5 is a right side elevational view of the charm of FIG. 1;

FIG. 6 is a top plan view of the charm of FIG. 1; and,

FIG. 7 is a bottom plan view of the charm of FIG. 1.

The broken lines in FIGS. 1-7 represent environment and are for illustrative purposes and do not constitute part of the claimed design.

The phantom lines in FIGS. 1-7 represent the boundary between claimed and unclaimed matter.
